UNITED STATES PATENT OFFICE.

FRANK DELLA TORRE, OF BALTIMORE, MARYLAND.

METHOD FOR FOCUSING APPLIANCES ON DISTANT OBJECTS.

1,326,549.

Specification of Letters Patent. Patented Dec. 30, 1919.

Application filed October 27, 1916. Serial No. 128,164.

To all whom it may concern:

Be it known that I, FRANK DELLA TORRE, a citizen of the United States, residing at Baltimore city, in the State of Maryland, 5 have invented a certain new and useful Method for Focusing Appliances on Distant Objects, of which the following is a specification.

My invention relates to an improved method 10 of for locating a distant object and focusing a coöperating appliance upon the same, and has for its object the observing of a distant object acoustically, and contemporaneously therewith, coöperatively controlling an appliance for acting upon said object, and has particular reference to the controlling of a beam of light or the course of a projectile to said object.

A further object of my improved method 20 for focusing appliances on distant objects, is, an improved method of directing an appliance toward an object in azimuth, obscure to the ordinary vision.

A further object of my improved method 25 for focusing appliances on distant objects, is, an improved method for directing an appliance toward an object in transit, obscure to the ordinary vision.

A further object of my improved method 30 for focusing appliances on distant objects, is, an improved method for directing an appliance toward an object in azimuth and transit, obscure to ordinary vision.

With the foregoing and other objects in view, my invention consists of the novel treatment, combination and arrangement of methods herein described, and demonstrated by the accompanying drawings, wherein is shown an apparatus capable of having my 40 method practised therewith, but it is understood that changes, variations and modifications can be resorted to which come within the scope of the claims hereunto appended.

To better illustrate my invention, I will 45 take an example and illustrate the same.

As a concrete example, it is desired to locate an object such as an aeroplane in the air on a dark night, when nothing can be seen of the same and only the noise of its 50 engine can be heard, it being desired to definitely locate the same in the darkness and focus a searchlight so that a beam of light may be instantly thrown upon the same without previous search of the heavens, thus 55 eliminating the searching beam at random, which the aeroplane might be able to avoid;

or, in place of the searchlight a gun may be the coöperating member, from which a projectile may be fired, without warning, at the aeroplane (and directed toward the same). 60

To more fully elucidate my method I would refer to the accompanying drawings, in which, Figure 1 is a view in elevation of an appliance, such as a searchlight provided with azimuth and transit vibrating planes, 65 the operator A being in position to operate azimuth vibrator 2, operator B having stepped aside so as to give a better view of the appliance. Fig. 2 is a plan view of that shown in Fig. 1, the operators being omitted; 70 Fig. 3 is a view taken at right angles, and in elevation to that shown in Fig. 1, operator A having stepped aside so as to give a better view of the appliance, operator B being in position to operate transit vibrator 3. Fig. 4 75 shows an enlarged plan view of the device used to shift from azimuth to transit vibrations when one operator is used; Fig. 5 is a view taken in elevation to that shown in Fig. 4 and Fig. 6 is an end view in elevation of that shown in Fig. 4.

Similar numerals refer to similar parts throughout the several views.

1 is the appliance, such as a searchlight, but as suggested above a gun, telescope or other 80 appliance may be used. 2 is the azimuth vibrator mounted on searchlight 1 in azimuth; 3 is the transit vibrator mounted on searchlight 1 in transit.

For range finding purposes, azimuth 85 graduations are provided at 4 and transit graduations at 5, the appliance being either permanently set or its stand leveled by leveling screws 6.

The vibrating planes are provided on the insides with wave receivers 7, 8, 9 and 10, which receivers are connected to ear-pieces 11, 12, 13 and 14 respectively, where two observers are used, where one observer is used, one pair of ear-pieces only is provided, and means are provided for switching from the receivers on the azimuth vibrator to the receiver on the transit vibrator, such as a blanking device, damper, valve or the like 15. 95

When one observer is used ear-pieces 11, 12, 13 and 14 are disconnected from connecting pipes 16, 17, 18 and 19 respectively, which pipes 13, 17, 18 and 19 are then slipped on or secured to pipes 20, 21, 22 and 23, and ear-pieces 11 and 12 are slipped on to blanking device 15, at pipes 24 and 25. 26 is a

foot treadle fulcrumed at 27 and to which cord 28 is attached. Cord 28 operates over pulley 29, and operates blanking device or valve 15 in such a manner that one operator, such as operator A, by means of his foot treadle 26, can shift from observing vibrator 2 to observing vibrator 3.

30 and 31 are shafts secured to trunnion supports 32 and 33 respectively and between 10 which operator A places himself, so that he may move the appliance (by means of his body) in azimuth; trunnion supports 32 and 33 being mounted on trunnion base 34, which trunnion base 34 is pivotally mounted on 15 level base 35. Appliance 1 is mounted by means of trunnions 36 and 37 in trunnion supports 32 and 33. On trunnion 37 is secured hand wheel 38 for rotating appliance 1 vertically.

20 Vibrator 2 is limited in its movements by stops 39 and vibrator 3 is limited in its movements by stops 40; the range of vibrators in practice is any convenient arc, such as twenty degrees from the axes of the appliance. 41 is a hand wheel attached to vibrator 2 and operates the same; 42 is a hand wheel attached to vibrator 3 and operates the same. 43 is a switch in the appliance shown for operating the light by throwing 25 the current on and off.

The practice of my method is as follows:

Wishing to get the bearing of a distant acoustic disturbance such as might be observed from soaring aircraft, preferably two 35 operators are employed; one making the vertical or transit observations, and the other the horizontal or azimuth observations; this may be accomplished by both observing operators controlling a single appliance or one vibrator in azimuth with one operator may be used with one appliance and another operator in observing in transit may be used with another appliance; two appliances being used such as is now common in 40 searchlight observations working in conjunction, and in this connection I wish it understood that I do not wish to limit myself in the practice of my method to the instrument shown in the drawings as my 45 azimuth and transit vibrators may be at a distance from the coöperatively controlled appliance and from each other and the said appliance controlled by well known synchronizing apparatus.

50 The operators having taken their respective positions, vibrate their vibrators in limited arcs, causing the planes of the vibrators to approach a normal position to the sound wave, by observing the intensity 55 of the same on the sides of the vibrators and directing the planes thereof toward the greatest intensity, until such a point is reached that the wave is split, and equal intensity of wave is observed on either side 60 of the vibrators, at which point the distant

acoustic disturbance is in the planes of the vibrators.

The two vibrators having their planes at an angle with reference to each other, the common intersection of the planes of the vibrators when the intensity of the received wave is equal on all faces is the normal line of transmission of acoustic disturbance desired.

Having thus described my invention, what 75 I claim and desire to secure by Letters Patent is:

1. Method of focusing an appliance consisting of, receiving vibrations upon the opposite faces of planes vibrating on a plurality of axes changed to receive similar vibrations from said planes and then focusing the axis of said appliance normal to the said vibrations.

2. Method of locating an object consisting of, receiving vibrations emanating from an object to be located along the intersection of a plurality of intersecting planes placed in the line of transmission normal to 80 said vibrations.

3. Method of locating an object consisting of, receiving vibrations emanating from an object to be located along the intersection of a plurality of intersecting planes placed in the line of transmission normal 95 to said vibrations and then focusing the axis of said appliance in said line.

4. Method of locating an object consisting of, initially receiving vibrations therefrom in one of the quadrants of normally 100 bisecting planes, then vibrating said two planes to a point of rest parallel to the line of transmission of said vibrations.

5. Method of locating an object consisting of, simultaneously receiving vibrations 105 therefrom on two angularly disposed planes provided with receiving instruments on each side of said two planes for independently determining the relative intensity of the received vibrations on the respective sides of 110 said two planes, and then vibrating said planes until the relative intensity of vibrations received on the various sides of the said two planes are equal.

6. Method of locating an object consisting of, initially receiving vibrations therefrom in one of the quadrants of normally 115 bisecting planes, then vibrating said two planes to a point of rest parallel to the line of transmission of said vibrations, said 120 planes being provided with means of determining the relative intensity of vibrations on the respective faces thereof.

7. Method of locating an object consisting of, initially receiving vibrations therefrom in one of the quadrants of normally 125 bisecting planes, then vibrating and rotating said two planes to a point of rest parallel to the line of transmission of said vibrations.

3. Method of locating an object consisting of, simultaneously receiving vibrations therefrom on two angularly disposed planes provided with receiving instruments on each side of said two planes for independently determining the relative intensity of the received vibrations on the respective sides of said two planes, and then vibrating and rotating said planes until the relative intensity of vibrations received on the various sides of the said two planes are equal.
